FREEZING TRAY RELEASE

James H. Dennedy, Evansville, Ind., assignor to
Sunbeam Electric Manufacturing Company,
Evansville, Ind., a corporation of Indiana

Original application July 16, 1934, Serial No.
735,371. Divided and this application Decem-
ber 3, 1936, Serial No. 113,965

8 Claims. (Cl. 62—108.5)

My invention relates to freezing tray releases and especially to mechanism for releasing the freezing trays or ice cube trays against the tendency of their bottom walls to freeze to the floors 5 or shelves on which they are supported in the evaporators or cooling units of domestic refrigerators.

Among the objects of my invention are: economy of manufacture; simplicity of operation; a 10 small space, especially in the vertical direction for the normal position of the release mechanism; elimination of the requirement for any special construction of the tray itself, whereby any 15 standard tray may be employed with the release; ready accessibility to the operator of the manually engaged portion of the release; the application of lifting pressure to the tray well back from the end thereof better to avoid permanent bending of the tray; mounting of the release mechanism on 20 a tray shelf without substantially perforating the shelf, whereby the release mechanism does not involve leakage of spilled water into the tray beneath; ready cleaning of the tray shelf or floor despite the mounting of the release mechanism 25 thereon; and a release mechanism so designed that it is not apt to become frozen itself, but which if frozen is readily releasable.

The foregoing together with further objects, features and advantages of my invention are set 30 forth in the following description of a specific embodiment thereof illustrated in the accompanying drawings, wherein:

Fig. 1 is a longitudinal vertical section through 35 a freezing unit of a domestic refrigerator showing the tray supporting shelf and bottom in section but the header in elevation, which may be considered as taken on the line 1—1 of Fig. 3;

Fig. 2 is a plan section taken on the line 2—2 of Fig. 1;

Fig. 3 is a transverse vertical section taken on the line 3—3 of Fig. 1 and looking forwardly;

Fig. 4 is a perspective view of the rod constituting the moving part of the tray release;

Fig. 5 is a fragmentary vertical section taken 45 on the line 5—5 of Fig. 2 showing the bearing arrangement for the shaft portion of the release rod; and

Fig. 6 is a fragmentary section similar to the lower right-hand corner of Fig. 1, but showing a 50 modified form in which the false bottom is omitted.

This application is in the nature of a division of my application Serial No. 735,371 filed July 16, 1934, Patent No. 2,130,331, dated Sept. 13, 1938, 55 on Cooling units. Reference is made to that ap-

plication for details of the freezing unit in which the tray release of the present invention is incorporated in this illustrative embodiment of my invention.

The cooling unit designated as a whole by the 5 reference character 10 comprises in general a shell 11 formed from sheet metal, a header 12 and a plurality of more or less U-shaped lengths of tubing 13, having their ends communicating with the header and received in corrugations 14 in the 10 shell 11. Refrigerant passes to the header 12 of this evaporator through an inlet tube 15. A horizontal U-shaped portion 16 is incorporated in the inlet tube 15. This U-shaped portion 16 is received in a similar shaped corrugation 17 impressed from the underside in a sheet metal shelf 18 which constitutes the support for the upper freezing tray here shown. A transverse embossure 19 toward the forward edge of the shelf and substantially the same height as the embossed 20 corrugations 17 is adapted to support the forward end of the upper freezing tray 20. Since the tray rests only on the bead-like upper edges or crowns of the embossures 17 and 19, the area of contact with the tray is minimized, thereby minimizing the area to which the tray can freeze. 25

The lifting jack 21 or moving part of the tray release of my invention, as here shown incorporated on the shelf 18, comprises a rod bent to form a transversely journaled shaft portion 22, a 30 forwardly extending lever portion 23 at substantially right angles to the shaft portion, an in-turned handle or finger engaging portion 24 at the forward end of the lever portion 23, and a crank portion 25 midway of the shaft portion 22. 35 If desired a vertical riser 26 may be incorporated in the forward end of the lever portion 23 where it joins the shaft portion 22.

Bearings 27 for the shaft portion of the lifting jack are provided in the shelf 18, one bearing on 40 each side of the crank portion 25. The bearings may advantageously be formed as follows: for each bearing a pair of spaced slits 28 are cut in the sheet metal of the shelf 18. Simultaneously the sheet metal between the slits is upwardly em- 45 bossed to form the upper half of the bearing 27. The lower half of the bearing is formed by a bearing strip 29 similarly corrugated, which is laid over the shaft portion 22 and spotwelded to the underside of the shelf. 50

In order to minimize the height of that portion of the release mechanism which underlies the tray, and especially to keep the overall height thereof as low as the plane of the corrugations 17 and embossure 19, the axis of the shaft por- 55

tion 22 is disposed in the plane of the field of the shelf 18. Accordingly the surface of the shelf on the distant sides of the bearings 27 is embossed downwardly as indicated at 30 to clear the ends of the shaft portion 22.

The crank portion 25 lies between the bearings 27 and to provide clearance for it, a circular depression 31 is embossed downwardly in the shelf.

10 It will be observed that this mounting for the shaft of the lifting jack affords no substantial openings through the shelf and that, therefore, if liquid should lie upon the shelf, it cannot readily drip through the shelf into the tray beneath.

15 This would be objectionable if, for example, the tray upon the shelf contained ice cream mix, some of which was spilled on to the shelf and leaked through the shelf to disfigure the water being frozen beneath.

20 The lever portion 23 of the lifting jack extends along the space between the side of the tray and the side wall of the freezing unit shell, where it is out of the way and inconspicuous. Preferably the lever portion 23 comes on the side 25 of the shell opposite the hinge edge of the freezer door 32, with which the freezing units are often provided. Thus, the door, when open, does not interfere with the hand in engaging the handle portion 24.

25 In operating the release mechanism, which of course has to be done only when the tray is frozen to the shelf, the handle portion 24 is engaged between thumb and finger and lifted upwardly which, through the lever portion 23, rotates the shaft portion 22 swinging the crank portion 25 upwardly against the bottom of the tray. The leverage afforded by the length of the lever portion 23 in proportion to the offset of the crank 25 permits a sufficient force to be applied to the bottom of the tray and free it from the shelf with relatively little finger pressure. The lifting jack will swing by gravity to its normal position illustrated, and this is further insured by the weight of the tray if the tray continues to rest upon the shelf.

30 It is particularly to be noted that the lifting jack is so designed that if it should itself become frozen to the shelf, but little effort would be required to free it. This is because the portion of the lifting jack which comes in contact with the shelf is chiefly the shaft portion 22, which will readily free itself by rotation. There is but a small portion—the crank 25—which involves more than a simple axial rotation to free itself of freezing, and this is not an appreciable additional burden upon the bigger pressure applied to the lifting jack for freeing the tray.

35 The lower freezing tray 33 may rest directly upon the bottom wall of the shell 11, as shown in the modification of Fig. 6, but preferably a false bottom 34 is employed. This has two-fold advantages. One is that the bearings for the lifting jack need not be incorporated in the shell itself, and the other is that the false bottom may conveniently be provided with corrugations or embostures 35, somewhat like the corrugations and embostures 17 and 19 in the shelf for minimizing the areas of contact with the tray bottom.

40 As applied to the false bottom of Fig. 1, an alternative bearing arrangement is disclosed wherein the bearing strips 29, which form the lower halves of the bearings and are disposed immediately beneath the upper halves of the bearings 27, are omitted. Instead the depressions 30 for the shaft portion 22 of the lifting

5 jack beyond the bearings 27 constitute the lower halves of the bearing. Thus the upper and lower halves of the bearings are axially offset. The bearing construction illustrated for the shelf may be incorporated in the bottom or false bottom, and conversely the bearing construction shown on the false bottom may be incorporated in the shelf.

55 While I have disclosed these specific embodiments of my invention, I contemplate that many changes and substitutions may be made without departing from the scope or spirit of this invention.

I claim:

1. The combination with a freezing compartment having a supporting floor for receiving an ice tray and a forward opening for insertion of the tray, of a tray release comprising a shaft portion journaled transversely of the floor and substantially in the plane thereof, a crank offset 20 in the shaft beneath the tray position, a depression in the floor normally receiving the offset, and a manually engageable portion fixed to the shaft portion and extending forward to said opening and laterally of the tray position for swinging said crank into lifting engagement with the bottom of the tray.

2. The combination with a freezing compartment having a sheet metal supporting floor for a freezing tray received within the compartment, 30 the floor having upwardly protruding corrugations embossed therein for minimizing the area of contact of the bottom of the tray with the floor, of a tray release comprising a shaft portion disposed intermediate said corrugations and 35 transversely of the floor and along the top surface thereof, a pair of spaced bearings for the shaft portion formed from the sheet metal stock of the floor, a crank offset in the shaft portion intermediate the bearings, and a finger engageable 40 arm extending forwardly from one end of the shaft portion and disposed between the sides of the tray and the adjacent side wall of the compartment for rotating the shaft portion to swing the crank portion into lifting engagement with 45 the bottom of the tray.

3. The combination with a generally planar sheet metal support for the bottom of a freezing tray, of a release mechanism for freeing the tray from the support comprising a lifting jack having a shaft portion disposed substantially in the plane of the support beneath the tray position and extending transversely thereof, a pair of upper bearing portions semi-circular in cross section struck out from the sheet metal of the support and receiving the shaft portion of the lifting jack, the lifting jack having an offset crank portion intermediate the bearing portions, means carried by the support forming the lower half of a bearing for the shaft portion, and a lever portion of the jack extending longitudinally of, and at the lateral side of, the tray position for rotating the shaft portion and thereby raising the crank portion against the bottom of the tray.

4. The combination with a generally planar sheet metal support for the bottom of a freezing tray, of a release mechanism for freeing the tray from the support comprising a lifting jack having a shaft portion disposed substantially in the plane of the support beneath the tray position 70 and extending transversely thereof, a pair of upper bearing portions semi-circular in cross section struck out from the sheet metal of the support and receiving the shaft portion of the lifting jack, the lifting jack having an offset crank 75

portion intermediate the bearing portions, a pair of bearing strips having transverse corrugations of semi-circular cross section constituting the lower halves of the bearing and disposed beneath the struck out upper bearings, the strips being secured to the undersides of the sheet metal support, and a lever portion of the jack extending longitudinally of, and at the lateral side of, the tray position for rotating the shaft portion and thereby raising the crank portion against the bottom of the tray.

5. The combination with a generally planar sheet metal support for the bottom of a freezing tray, of a release mechanism for freeing the tray from the support comprising a lifting jack having a shaft portion disposed substantially in the plane of the support beneath the tray position and extending transversely thereof, a pair of upper bearing portions semi-circular in cross section struck out from the sheet metal of the support and receiving the shaft portion of the lifting jack, the lifting jack having an offset crank portion intermediate the bearing portions, a lower bearing for the shaft portion being embossed in the sheet metal of the support, and a lever portion of the jack extending longitudinally of, and at the lateral side of, the tray position for rotating the shaft portion and thereby raising the crank portion against the bottom of the tray.

10. 6. The combination with a generally planar sheet metal support for the bottom of a freezing tray, of a release mechanism for freeing the tray from the support comprising a lifting jack having a shaft portion disposed substantially in the plane of the support beneath the tray position and extending transversely thereof, a pair of upper bearing portions semi-circular in cross section struck out from the sheet metal of the support and receiving the shaft portion of the lifting jack, the lifting jack having an offset crank portion intermediate the bearing portions, means

carried by the support forming the lower half of a bearing for the shaft portion, a lever portion of the jack extending longitudinally of, and at the lateral side of, the tray position for rotating the shaft portion and thereby raising the crank portion against the bottom of the tray, and a depression formed in the sheet metal support intermediate the bearing portions for reception of the crank portion.

7. The combination of a horizontally disposed generally planar sheet metal support for the bottom of a freezing tray, a lifting jack having a shaft portion disposed transversely of the support on its upper side and at a substantial distance rearwardly of its forward edge, a bearing for the shaft carried by the support, a crank portion offset from the shaft portion, and adapted upon rotation of the shaft to engage the bottom of the tray for lifting it, and a lever portion for the lifting jack extending forwardly from the shaft portion and at the side of the tray position and to the forward edge of the tray support for manual engagement to rotate the crank. 10 15 20

8. The combination of a horizontally disposed, generally planar sheet metal support for the bottom of a freezing tray, a lifting jack having a shaft portion disposed transversely of the support on its upper side and at a substantial distance rearwardly of its forward edge, a bearing for the shaft carried by the support, a crank portion offset from the shaft portion, and adapted upon rotation of the shaft to engage the bottom of the tray for lifting it, and a lever portion for the lifting jack extending forwardly from the shaft portion and at the side of the tray position and to the forward edge of the tray support for manual engagement to rotate the crank, the lifting jack being formed of a single continuous length of rod.

JAMES H. DENNEDY. 40
